FIG. 1 is a front perspective view of a tote bag with surface ornamentation showing our new design;

FIG. 2 is a top plan view thereof;

FIG. 3 is front elevational view thereof;

FIG. 4 is a left side elevational view thereof;

FIG. 5 is a rear elevational view thereof;

FIG. 6 is a right side elevational view thereof; and,

FIG. 7 is a bottom plan view thereof.

The characteristic feature of the design resides in the surface ornamentation, on the front and rear view, where the shading is used to show the contrast in color between the background of the fabric and the four-longhorn design.
